LID LIFTER AND CARRIER

Albert M. Lewis, Detroit, Mich.

Application June 13, 1947, Serial No. 754,397

4 Claims. (Cl. 214—65.4)

1

My invention relates to a new and useful improvement in a lid lifter and carrier adapted for use on containers having a removable lid which is of such proportions as to render it difficult to raise it by hand.

It is an object of the present invention to provide a lid lifter and carrier of this class so constructed and arranged that it may be advanced to the receptacle connected to the lid and automatically lift the same and retain it in lifted position so that the lid may be transported away from the container, thus making it possible to use the lid on different containers, if desired.

Another object of the invention is the provision of a device of this class which will be simple in structure, economical of manufacture, durable, compact, easily operated and highly efficient in use.

Another object of the invention is the provision in a device of this class of means of retaining the lid in fastened condition when the carrier is once fastened thereto.

Other objects will appear hereinafter.

It is recognized that various modifications and changes may be made in the detail of structure illustrated without departing from the invention itself and it is intended that such shall be embraced within the scope of the claims which form a part hereof.

Forming a part of this specification are drawings in which:

Fig. 1 is a perspective view of the invention,

Fig. 2 is a side elevational of the invention showing it applied with parts broken and parts shown in section;

Fig. 3 is a fragmentary view taken on line 3—3 of Fig. 2,

Fig. 4 is a slightly enlarged fragmentary, perspective view showing a part of the invention,

Fig. 5 is a slightly enlarged fragmentary view taken on line 5—5 of Fig. 1.

While the invention may be adapted for other uses, I intend that it be particularly adapted for use as a lid lifter and carrier. In the drawings, I have shown a receptacle 9 mounted on caster 10 and provided with a lid 11 having the depending flange 12 and the invention is illustrated as operating upon this lid 11.

The invention comprises a frame work embodying the rails 14 and 15, each of which is provided with the casters or rollers 16. Rails 17 and 18 serve to connect these rails or cross bars 14 and 15 to form a base. Projecting upwardly from this base is the inverted yoke or U-shaped member 19 which is braced to the member 14 and 15 by

2

the braces 20. Projecting outwardly from the legs of the inverted U-shaped member 19 are brackets or lugs 21 and 22. A supporting arm is pivotally connected at one end to the bracket 21 and a similar supporting arm 24 is pivotally connected at one end to the bracket 22. Carried by and connecting the arms 23 and 24 is a supporting plate 25 having the concave upper face 26.

Mounted on and projecting angularly upwardly from each of the members 14 and 15 is a cylinder 27 in which is slidably mounted a piston 28 having the piston rod 29 extended therefrom and pivotally connected at its upper end to the arm 23 or the arm 24. Positioned within the cylinder 27 is a coil spring 30 which is compressed when the piston 28 is moved downwardly.

A goose neck or rod 31 is rockably mounted on the U-shaped member by having the coil 32 formed therearound. This rod or goose-neck 31 is provided at its three ends with an eyelet 33 and slidably mounted on this rod 31 is a chain 34 carrying at its end the engaging hook 35.

Connected at one end to the rod 31 is a rod 36, the opposite end of which is pivotally connected to the rocker 37 which is pivotally connected at one end to the bracket 38 on the rod 15. This rocker 37 is connected by the connecting rod 39 to the supporting plate 25, the connections of the rod 39 at its opposite end being a pivotal connection. Mounted on each of the legs of the U-shaped member 19 is a supporting bracket 40 having the upwardly turned portion 41 which is formed arcuate to prevent a concave surface adapted to engage the curved surface of the lid or cover 11.

The mechanism described is, of course, transportable and may be easily moved about over the floor. In use, it is moved into engagement with the side of the lid or covers 11 and the operator then standing with the receptacle between him and the mechanism would reach up, by gripping the hook 35, and rock the members 31 downwardly. This would cause the arms 23 and 24 to rock downwardly and the plates 25 to tilt. This downward movement of the arms 23 and 24 would, of course, be against the compression of the spring 30. The operator would then engage the hook 35 around the edge of the flange 12 and when the hook is so engaged, the operator would then release the rod 31 of the downward pull. The piston rods 29 would then rock the arms 23 and 24 upwardly, the edge of the lid or cover 11 dropping on the supporting plate 25. Due to the curved upper surface of this supporting plate 25, the lower edge of the cover or lid could not rock

off of it. This upward rocking movement will continue until the cover or lid engages the engagement members 40, whereupon the entire structure may be transported from place to place, the lid being securely held in position.

After a lid or cover has been mounted on the carrier as described and it is desired to replace the lid or cover on the receptacle, it is but necessary to move the structure into the full line position shown in Fig. 2. The operator then while standing at the opposite side of the receptacle or container 9 would pull downwardly on the eyelet 33, this eyelet serving as a hand grip. This would permit the lid or cover to rock downwardly from the full line position shown in Fig. 2 to the dotted line position.

The structure, therefore, provides a means for lifting the cover from the receptacle and transporting it away from it and, also, a means for replacing the cover on the receptacle. The structure has proven most efficient in use, particularly, where the cover is of great weight or where it is of bulky size and not easily handled by a man. The operation of the device is one which may be easily and quickly performed so that a single individual may easily and quickly remove a weighted cover from the container in the manner described.

What I claim as new is:

1. A lid lifter and carrier of the class described, comprising: a base; traction members for supporting said base; a supporting member secured to and projecting upwardly from said base; a rocker swingably mounted at one end on said base and swingable upwardly and downwardly at its free end and normally positioned above said base; a pair of spaced apart arms mounted on said supporting member and swingable upwardly and downwardly at their outer ends; a lid engaging plate carried on the outer ends of said arms; a connecting rod for connecting said plate to said rocker; an engaging hook swingably mounted on said supporting member and overlying said base and said plate and swingable downwardly into position for engaging the edge of a lid to be lifted, said plate being adapted for engaging the opposite edge of said lid; a rod connecting said hook and the free end of said rocker for effecting, upon rocking movement of said rocker, simultaneous movement of said hook and said plate; and resilient means for normally retaining said swingably mounted arms in elevated relation and retaining said rocker in upwardly rocked position.

2. A lid lifting device of the class described, adapted for lifting a lid from a container, comprising: a supporting base; a supporting member mounted on and projecting upwardly from said base; an engaging plate for engaging one edge of a lid to be lifted; means for connecting said engaging plate swingably to said supporting member for swingable movement downwardly and upwardly at its engaging edge; an engagement member mounted on said supporting member and swingable downwardly and upwardly and adapted upon downward swinging for engaging the opposite edge of said lid and upon upward swinging for rocking said lid upwardly while en-

gaged at one edge on said plate; and means for simultaneously swinging said plate and said engagement member upwardly and downwardly; and resilient means for normally resisting swinging movement of said engagement member and said plate.

3. A lid lifting device of the class described, adapted for lifting a lid from a container, comprising: a supporting base; a supporting member mounted on and projecting upwardly from said base; an engaging plate for engaging one edge of a lid to be lifted; means for connecting said engaging plate swingably to said supporting member for swingable movement downwardly and upwardly at its engaging edge; an engagement member mounted on said supporting member and swingable downwardly and upwardly and adapted upon downward swinging for engaging the opposite edge of said lid and upon upward swinging for rocking said lid upwardly while engaged at one edge on said plate; and means for simultaneously swinging said plate and said engagement member upwardly and downwardly; and resilient means for normally resisting swinging movement of said engagement member and said plate; and means on said supporting member for engaging a lid when lifted upwardly on said plate.

4. A lid lifting device of the class described, adapted for lifting a lid from a container, comprising: a supporting base; a supporting member mounted on and projecting upwardly from said base; an engaging plate for engaging one edge of a lid to be lifted; means for connecting said engaging plate swingably to said supporting member for swingable movement downwardly and upwardly at its engaging edge; an engagement member mounted on said supporting member and swingable downwardly and upwardly and adapted upon downward swinging for engaging the opposite edge of said lid and upon upward swinging for rocking said lid upwardly while engaged at one edge on said plate; and means for simultaneously swinging said plate and said engagement member upwardly and downwardly; and resilient means for normally resisting swinging movement of said engagement member and said plate; and means on said supporting member for engaging a lid when lifted upwardly on said plate; and traction members for supporting said base.
